UNITED STATES PATENT OFFICE.

CHARLES J. ALLEN, COMMODORE P. WILDEN, AND CHARLES M. WILDEN, OF PORTLAND, OREGON.

MATTRESS.

Application filed April 27, 1921. Serial No. 464,826.

To all whom it may concern:

Be it hereby known that we, CHARLES J. ALLEN, COMMODORE P. WILDEN, and CHARLES M. WILDEN, citizens of the United States, and residents of Portland, in the county of Multnomah and State of Oregon, have invented a new and useful Mattress, of which the following is a specification.

This invention relates more particularly 10 to mattresses for use on beds.

The object of our invention is chiefly to provide a mattress which will not bulge at the sides when compressed, and at the same time increase the resiliency of the mattress 15 with a given amount of material and also to prevent the filling from shifting. A further object of our invention is to eliminate in its manufacture the necessity of using expensive tufting and roll edge machines, to make 20 the mattress practically vermin proof by the elimination of tufting and rolled edges, and to provide a mattress which will not vary in size under compression or use.

We attain these results in the manner set 25 forth in the following specification and illustrated in the accompanying drawing, in which:

Figure 1 is a plan of the mattress of which Figure 2 is a front elevation with a portion 30 cut away to show construction.

Similar numbers of reference refer to the same or similar parts throughout the views.

Referring in detail to the drawing, we have constructed our mattress of four sheets 35 of ticking 10, 11, 12 and 13 all of equal size, and separated to form three compartments. These four sheets 10 to 13 are held in the proper relation by a side wall piece of ticking 14 which extends about the perimeter of 40 the mattress and is securely sewed to each of the members 10 to 13 all the way around.

The compartments thus formed are preferably filled with silk floss, but cotton or other materials may be used if desired. Ordinarily no tufting whatever is used, but conditions may arise when it will be desirable to run a row of tufting along the lines A—B or C—D, or both.

We have also provided on the long sides 50 of this mattress the strips 15 securely fastened to the ticking of the mattress for the purpose of handling same, since it would be quite difficult to do so otherwise in the absence of a rolled edge.

Since it is found in practice that the major 55 portion of the labor charge in the construction of mattresses is made up by tufting and edge rolling, it will be observed that we have eliminated both of these operations, as well as the machines for performing same, thereby 60 tremendously reducing the manufacturing cost of the mattress, and in addition thereto have constructed a mattress with a wonderfully uniform top and edges, which can safely be guaranteed to hold its shape 65 for the life of the fabric from which it is constructed.

In the use of certain materials for filling it may prove expedient to run one or two 70 rows of stitching across the two center lines A—B and C—D of the mattress in order to prevent collapsing of the mattress when shipped. It is desirable to eliminate all tufting in the ordinary sense of the word, inasmuch as aside from the expense of installing, it must also be accompanied by increasing the sizes of ticking to make up for 75 the material in the tufts, and the tufts when pulled down tightly furnish concealment for dust and vermin. It must be understood 80 that this stitching or lacing is not drawn down tight as are tufts, but is loose enough to permit the cover to spread the full height of the sides. One continuous thread is used 85 to sew clear across the mattress in zig zag fashion and the thread is secured only at the ends.

It will be understood that mattresses have been manufactured employing one dividing sheet and including tufting. We are able 90 to dispense with the tufting and to increase the resiliency of the mattress by increasing the number of dividing sheets, for the following reasons: Each sheet produces a friction with the filling proportional to the 95 weight above same. Consequently the greater the number of horizontal sheets, the greater the resistance to lateral movement by the filler until the point is reached where even the tendency of shifting of the filler is overcome. After this point is reached it is not profitable to add more sheets, since the cost increases out of proportion to the advantage gained. In addition to this, there is still another advantage in the multiple 100 sheet mattress. This is the distribution of strains between all of the sheets which are also held by the same friction of the filler,

whereas if only one dividing sheet is used, there is not sufficient friction to withstand the outward pull on the sheet.

The added resilience is due to the fact that 5 this construction has produced a number of superimposed hammocks held in suspension, partially by the side walls and partially by the friction between the sheet and the filler beneath and above same rather than being 10 supported by the resilience of the filler itself.

We are aware that numerous mattresses have been constructed along somewhat 15 lines. We therefore do not claim our invention broadly but only within the limits set forth in the following claims.

What we claim as new is:

1. An untufted mattress without rolled edges having a loose filling and having a plurality of stretchless horizontal dividing

means between its top and bottom and attached by their outer edges to the sides of the mattress, said dividing means and said top and bottom having exactly the same size, said dividing means being sufficient in number to prevent the shifting of the filling 25 without the use of tufting.

2. In a tuftless mattress the combination of a mattress covering and filling with means for preventing the filling from shifting consisting of a plurality of stretchless sheets 30 sewed to the sides of said mattress between its top and bottom, said sheets having exactly the same area before and after assembling as do said top and bottom members.
